CLAIM

The ornamental design for a dispensing pump head, as shown and described.

DESCRIPTION

FIG. 1 is a perspective view of the front and right side of the dispensing pump head;

FIG. 2 is a perspective view of the front and right side of the dispensing pump head, the broken line depiction of a representative bottle forming no part of the claimed design;

FIG. 3 is an elevational view of the left side of the dispensing pump head;

FIG. 4 is an elevational view of the right side of the dispensing pump head;

FIG. 5 is a elevational view of front of the dispensing pump head;

FIG. 6 is an elevational view of the rear of the dispensing pump head;

FIG. 7 is a top plan view of the dispensing pump head; and,

FIG. 8 is a bottom plan view of the dispensing pump head.
